UNITED STATES PATENT OFFICE.

WILLIAM J. KNOX, OF DUBOIS, PENNSYLVANIA.

VALVE-CHEST CONSTRUCTION FOR STEAM ENGINES.

Application filed February 9, 1924. Serial No. 691,575.

To all whom it may concern:

Be it known that I, WILLIAM J. KNOX, a citizen of the United States, and a resident of Dubois, in the county of Clearfield and State of Pennsylvania, have made a new and useful invention in Improvements in a Valve-Chest Construction for Steam Engines, of which the following is a specification.

10 The invention relates to valve chest constructions for steam engines, and particularly locomotive engines, in which it is desired to substitute piston valves for the slide valves in order to adapt the engines to the use of superheated steam at high temperature, it being recognized as impracticable to use superheated steam with slide valves because of the difficulty of lubricating such valves. Various expedients for making such substitution have been attempted, calling for special steam chests and valve chambers bolted to the cylinders and employing gaskets to insure tight joints between the parts, but in practice, it has been found very difficult to make the joints tight and maintain them in such condition in service. It is the object of the present invention to overcome this difficulty and provide a construction which can be applied without difficulty, and at a reasonable cost.

In the construction, as hereinafter described, and illustrated in the drawings, the steam chest is held in place on the cylinder in the usual way by studs with nuts and by bolts, with a gasket for securing a tight joint. Inside this chest is a valve casing, or chamber member, in the form of a casting carrying a piston valve. This casing is secured in place on the cylinder by the autogenous welding process, and when welded in place, becomes in effect integral with the cylinder, so that there is no possibility of leakage. As locomotive cylinders are practically all cast of grey iron, which does not readily yield to the welding process, a false valve seat of open hearth steel, or wrought iron, which is readily weldable, is fitted to the face of the cylinder surrounding the ports, and secured rigidly in place. The valve casing or chamber member is a steel casting, which is readily weldable to the false seat. If the cylinder proper should itself be a steel casting, or of a material which is readily weldable, the false valve seat may be dispensed with. One embodiment of the

invention is illustrated in the accompanying drawings, wherein:

Figure 1 is a longitudinal section through the cylinder face, the steam chest, valve chamber, valve chamber bushing, valve and associated parts. Fig. 2 is a plan section of the chest and valve chamber taken on the line II—II—II of Fig. 1. Fig. 3 is a half cross section on the line III—III of Fig. 1, and a half elevation of the right hand end of the chest. Fig. 4 is a plan section through the chest, one half the valve chamber being shown in place, while in the other half it is omitted to better show the ports and false valve seat. Fig. 5 is a half plan and half section of the valve chamber on the line V—V of Fig. 7. Fig. 6 is a vertical section of the valve chamber taken on the line VI—VI of Fig. 7. Fig. 7 is a half cross section and half end view of the valve chamber. And Figs. 8 and 9 are plan and elevation views respectively of the cover strip.

Referring to the drawings, 1 is the engine cylinder having the steam ports 2 and 3 and the exhaust port 4 of the usual construction. Mounted on the upper side of the cylinder wall and surrounding the ends of the ports is the false valve seat 5 which is secured in place by means of the bolts 6, such seat being of a readily weldable metal such as wrought iron or open hearth steel.

Mounted upon the seat is the valve casing or chamber 7, such casing being of cast steel or other metal which can be welded. This casing is secured to the seat 5 by welding it at the edges, inside and out, along the lines 8, 9, 10, 11, 12 and 13. The inside welding along the lines 9 and 10 is accomplished through the opening 14 (Figs. 1 and 7) in the top of the casing, before the segmental cover strip 15 is applied, such strip being secured in position by welding along the lines 16.

The casing 7 is also provided with the cross walls 17, 18, 19 and 20 (Fig. 2), and through these walls circular holes are bored in true alignment, and in these is pressed or shrunk the valve bushing 21. The valve 22 shown is of the double piston head and spool type, but any suitable piston valve may be employed, and motion is imparted to it through the stem 23 connected to the usual valve motion.

Fitting over the valve casing 7 is the

steam chest 24, such chest being secured in place by the stud bolts 25 screwed into the cylinder wall at their lower ends and provided with the nuts 26. Additional securing means at the rear end of the chest is provided by the bolts 27, which extend through the bottom wall of the steam chest (Figs. 1 and 2) and into the top cylinder wall. The rear end of the steam chest is provided with a D shaped opening 28, to permit the insertion and removal of the valve without disengaging the chest from the cylinder. This opening is closed by the cover plate 29 secured by the bolts 30. This opening also permits of the introduction of the two bolts 27. Suitable gaskets to prevent leakage are provided beneath the heads of these bolts and also between the lower edges of the chest and the upper face of the cylinder upon which the chest is supported.

It will be seen that the improved structure achieves the objects heretofore set forth. The casing or chamber 7 is attached very securely to the false seat by the welding operation, and the lines of welding, in addition to securing the chamber securely in place, prevents the passage of steam from port to port and also the passage from the chest to the middle section of the valve. The welding on the inside lines 9 and 10 is made possible by the use of the arc shaped opening 14 which is subsequently permanently closed by the cover strip 15. The structure is readily applicable to practically all engines heretofore equipped with slide valves at a relatively low cost and with a resulting structure of a most substantial character which requires a minimum of attention in maintenance, and in which any leakage at the joints is reduced to a minimum. The false seat 5 can be secured so that there is no leakage between its lower surface and the top surface of the cylinder surrounding the parts, since the bolts or screws 6 can be placed closely enough to secure this result, and can also be placed through the strips lying between the central port 4 and the ports 2 and 3, so that there is no leakage beneath these strips. If the false seat were dispensed with, it would be practically impossible to secure the casing down upon the top surface of the cylinder by screws or bolts in such manner as to prevent leakage, because of the difficulty of locating the screws or bolts around the periphery of the casing in such manner as to make a permanently tight joint, and because screws could not be inserted through the strip portions lying between the port 4 and the ports 2 and 3. Without tight joints at these latter points, leakage would occur between the ports.

What I claim is:

1. The combination with a cast cylinder of metal not readily subject to a welding

operation and having ports through one side, of a seat, comprising a sheet of weldable material secured to the cylinder by screw means and surrounding the ports, a valve casing mounted on such seat and welded thereto along its periphery and also interiorly along lines lying between the ports, a piston valve mounted in the casing, and a steam chest surrounding the valve casing secured to the cylinder.

2. The combination with a cast iron cylinder having ports through one side and a seat, comprising a sheet of weldable metal surrounding the ports secured by screw means to such cylinder with a steam-tight joint, a valve casing mounted on such seat and welded thereto around its periphery and also along lines between the ports, a piston valve mounted in the casing, and a steam chest surrounding the valve casing and secured to the cylinder.

3. The combination with a cast cylinder of metal not readily subject to a welding operation and having ports through one side, of a seat comprising a sheet of weldable material secured to the cylinder by screw means and having a steam-tight contact therewith, a valve casing mounted on such seat and welded thereto along both its inner edges and its outside edges, and having an opening through its upper side for giving access to the interior for the welding operation along said inside edges, a cover plate for said opening, a piston valve mounted in the casing, and a steam chest surrounding the casing and secured to the cylinder.

4. The combination with a cast cylinder of metal not readily subject to a welding operation and having ports through one side, of a seat comprising a sheet of weldable material secured to the cylinder by means of a series of screws and surrounding the ports, a valve casing mounted on such seat and welded thereto along both its inside edges and its outside edges and having an opening through its upper side for giving access to the interior for the welding operation, a cover plate for said opening welded to the casing, a piston valve mounted in the casing and a steam chest surrounding the casing and secured to the cylinder.

5. The combination with a cast cylinder of metal not readily subject to a welding operation and having ports through one side, of a seat of weldable material secured to the cylinder by a series of screws having a steam-tight contact therewith and surrounding the ports, a valve casing mounted on such seat and welded thereto and provided with ports, and having an opening through its upper side for giving access to the interior for the welding operation, a cover plate for said opening, a piston valve mounted in the casing, a steam chest sur-

rounding the casing and secured to the cylinder, a removable cover plate for one end of the steam chest in alignment with said valve, and securing stud bolts extending through the lower wall of the steam chest into the cylinder wall and having their heads accessible through the end of the steam chest when the cover plate is removed.

6. The combination with a cylinder having ports through one side and a seat surrounding the ports, of a valve casing mounted on such seat and secured thereto and provided with ports, a piston valve in

the casing, a steam chest surrounding the casing and bolted thereto with an opening 15 at one end opposite the end of the piston, a removable cover plate for said opening, and securing stud bolts extending through the lower wall of the steam chest into the cylinder wall and having their heads accessible 20 through the end of the steam chest when the cover plate is removed.

In testimony whereof, I have hereunto subscribed my name this 6th day of February, 1924.

WILLIAM J. KNOX.
